C. J. PERKINS.

DOOR FOR SILOS.

APPLICATION FILED MAR. 3, 1913.

1,081,863.

Patented Dec. 16, 1913.

UNITED STATES PATENT OFFICE.

CHARLES J. PERKINS, OF MANITOU, COLORADO, ASSIGNOR OF ONE-THIRD TO JOHN T. M. JOHNSTON AND ONE-THIRD TO JAMES F. HOLDEN, BOTH OF KANSAS CITY, MISSOURI.

DOOR FOR SILOS.

1,081,863.

Specification of Letters Patent.

Patented Dec. 16, 1913.

Application filed March 3, 1913. Serial No. 751,955.

To all whom it may concern:

Be it known that I, CHARLES J. PERKINS, a citizen of the United States, and a resident of the city of Manitou, county of El Paso, and State of Colorado, have invented 5 certain new and useful Improvements in Doors for Silos, of which the following is a specification.

My invention relates to silos and more 10 specifically to improvements in the construction of the doorways of silos.

The object of my invention is the production 15 of a silo in which will be provided a door structure which will be durable and economical in construction, built to withstand the influences of the weather or fire, and which will be efficient in use.

Other objects will appear hereinafter.

The invention consists in the combinations 20 and arrangements of parts hereinafter described and claimed.

The invention will be best understood by reference to the accompanying drawing forming a part of this specification, and in 25 which,

Figure 1 is a horizontal section of a silo through the doorway of the same illustrating the preferred form of my invention, the section being taken on substantially line 30 $x-x$ of Fig. 2, Fig. 2 is a vertical longitudinal section taken on substantially line $y-y$ of Fig. 1, Fig. 3 is a perspective view illustrating the arrangement of the cross pieces in the doorway of the silo, and 35 Fig. 4 is a perspective view illustrating the construction of the reinforcing bands employed in the structure.

The preferred form of construction as 40 illustrated in the drawing comprises a silo having a circular lateral wall 1 which is constructed of blocks 2 of plastic material such as concrete or cement, said blocks being preferably of the double wedge-shaped form, as shown in the drawing, the construction 45 of this wall being the subject matter of a copending application, Serial No. 751,956, filed March 3, 1913. The lateral wall 1 is reinforced at intervals by vertically spaced bands 3 which encircle said wall at 50 the outer side thereof. The bands 3 are arranged in annular grooves or channels 4 formed in the outer surface of the wall 1, plastic sealing material, and preferably mortar 5 being arranged over the bands 3 to

completely cover the same in order to protect 55 the same against corrosion.

Formed in one side of the lateral wall 1 is a vertically extending doorway 6 the opposite edges of which are parallel. Registering with the doorway 6 is the conventional chute 7 which may be of the same construction as the wall 1.

The doorway 6 is traversed at intervals by vertically spaced transversely extending members 8, said members 8 being formed of 60 plastic material, such as concrete or cement and are reinforced by longitudinally extending bars 9. The respective ends of the members 8 are set in the lateral edges of the doorway 6, the blocks 2 being cut away as 65 70 at 10 in order to receive said ends of said members, as clearly shown in Fig. 3. The reinforcing bands 4 at the doorway 6 are connected by means of socket members 11 with circular sections or bars 12, the respective 75 ends of which are threaded into the socket members 11, as clearly shown in Fig. 4. The members 12 engage elongated grooves or recesses 13 which are formed in the outer sides of the members 8, said sections 80 85 12 thus serving to securely hold said members 8 in operative position. In order to protect the reinforcing members 12 against corrosion or fire, sealing material such as mortar, as shown at 14, is arranged in said recesses over said members 12 to completely inclose the latter.

Removably arranged in the doorway 6 between the transversely extending members 8 are door sections 15, the peripheral 90 edges of said sections being beveled for engagement with the bevel edges 16 of the cross pieces 8 and the lateral edges of said doorway, as clearly shown in the several views. With this arrangement, it will be 95 seen that the door sections, when arranged in operative position, will be held against outward displacement, but will be free for inward movement so that as the ensilage in the silo is emptied therefrom, said door sections may be successively removed from the 100 inside to correspond with the level of the ensilage in the silo. With the arrangement disclosed it will be seen that each cross piece 8 will serve in the capacity of a sill for the 105 next upper door section 15 and as a cap stone for the next lower door section. Also, said cross pieces will serve as the rungs of

a ladder which may be utilized in climbing to the inside of the silo.

A doorway construction of the design set forth possesses durability, the same is simple and economical in construction, and hence may be manufactured at a low cost, and will be found highly efficient in use.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A silo comprising a lateral wall having a vertically extending doorway; transversely extending members traversing said doorway at intervals; and reinforcing bands encircling said silo and engaging against the outer sides of said transversely extending members, said outer sides of said members being provided with longitudinally extending recesses to accommodate said bands, substantially as described.
2. A silo comprising a lateral wall having a vertically extending doorway; transversely extending members traversing said doorway at intervals; reinforcing bands en-

circling said silo and engaging against the outer sides of said transversely extending members, said outer sides of said members being provided with longitudinally extending recesses to accommodate said bands; and sealing material arranged in said recesses over said bands completely inclosing the latter, substantially as described.

3. A silo comprising a lateral wall formed of plastic material, said wall having a vertically extending doorway; transversely extending members of plastic material traversing said doorway at intervals; reinforcing bands encircling said silo and engaging against the outer sides of said transversely extending members, said outer sides of said members being provided with longitudinally extending grooves for the accommodation of said bands; plastic sealing material arranged in said recesses over said bands completely inclosing the latter; and door sections arranged between said transversely extending members and engaging against the inner sides of the latter and the corresponding edges of said doorway, substantially as described.

In testimony whereof I have signed my name to this specification in the presence of two subscribing witnesses.

CHARLES J. PERKINS.

Witnesses:

JOSHUA R. H. POTTS,
HELEN F. LILLIS.
